UNITED STATES PATENT OFFICE.

JAMES H. McCALL, OF HUNTINGDON, TENNESSEE.

SANITARY ODORLESS TOILET.

Application filed December 19, 1923. Serial No. 681,613.

The primary object of this invention is to provide a novel and improved toilet for railroad cars or other passenger vehicles which is sanitary and also odorless.

Toilets of the kind now in general use on railway cars are subject to the objections that they are insanitary and they are odorous. In use, it is found that particles of excreta deposit and accumulate on the lower portion or edge of the toilet pipe, this occurring particularly when there is a shortage of flushing water, and when the toilet is dumped, which usually occurs while the car is in motion, the pivoted cup which normally closes the lower end of the toilet pipe, swings downwardly into a position which causes a draft of air upwardly through the thus uncovered open end of the pipe and into and through the bowl, this air draft carrying with it particles of excreta containing pathogenic bacteria which is inhaled or deposited upon the body of the person, thus subjecting the person to liability to infection with diseases of various kinds, and also causing a foul odor to pervade the toilet compartment, and, sometimes the entire car, to the danger and discomfort of the passengers.

The present invention provides a toilet which obviates these objections, it being so constructed that no upward air draft through the toilet pipe can take place, and hence neither bacteria nor odors can be blown into the toilet compartment or into the car.

To these and other ends, the invention consists in certain improvements and combinations and arrangements of parts, all as will be hereinafter more fully described, the features of novelty being pointed out particularly in the claims at the end of the specification.

In the accompanying drawings:—

Figure 1 is a side elevation of a sanitary toilet constructed in accordance with the preferred embodiment of the present invention;

Figure 2 represents, on an enlarged scale, a vertical section through a portion of the toilet discharge pipe showing the lower cup in closed position;

Figure 3 represents a top plan of the structure shown in Figure 2;

Figure 4 shows in elevation the double cup operating means in an intermediate position, at which time both cups are closed;

Figure 5 is a view similar to Figure 4, but showing the cup operating means fully actuated into dumping position, at which

time the upper cup is open and the lower cup is closed; and

Figure 6 represents a detail section on the line 6—6 of Figure 5.

Similar parts are designated by the same reference characters in the several views.

The present invention is applicable generally to toilets of the kinds suitable for use on railway passenger cars or coaches, passenger airships and in similar situations where strong air currents are present or are induced. The preferred embodiment of the invention is shown in the accompanying drawings and will be hereinafter described in detail, but it is to be understood that the invention is not restricted to the precise construction shown, as equivalent constructions are contemplated and such will be included within the scope of the claims.

In the present instance, 1 designates the bowl of a toilet having its outlet 2 connected preferably to a discharge pipe 3, the latter being of suitable length to suit any particular installation. According to the present invention, upper and lower cups 4 and 5 are provided which are arranged one above the other and are operative to so control the toilet pipe that when one of these cups is in open position, the other cup will be in completely closed position. Preferably and as shown in the present instance, means is provided for automatically actuating and controlling the cups so that the upper cup will be normally closed and the lower cup normally open, and when the mechanism is actuated into dumping position the lower cup is moved into fully closed position, while the upper cup remains closed, whereupon the upper cup moves into open position while the lower cup remains in closed position; and the return movement of the actuating mechanism first causes the upper cup to close during the period the lower cup remains closed, whereupon further return movement of the actuating mechanism causes the lower cup to open, during which period the upper cup remains closed. Different forms of mechanism may be employed for accomplishing these results.

As shown in the present instance, the upper cup is fixed to a shaft 6 which is suitably mounted rotatably in the wall of the toilet pipe 2 and extends outside thereof, and the lower cup 5 is fixed to a shaft 7 which may be rotatably mounted on the lower end of the pipe 2 or in the discharge pipe 3, this

2

shaft also extending to the outside of the pipe 3, the mountings of the cups being such that they may swing to and from closed position about the shafts 6 and 7, respectively, as axes. In the present instance, actuating and controlling cams 8 and 9 are fixed on the outer ends of the respective shafts 6 and 7. The cam 8 has an angularly offset cam slot 8^a therein, in which a pin 10 carried by a reciprocatory rod 11 operates, the cam slot being substantially aligned with the direction of movement of the rod 11, while the cup 4 is in closed position, this being the position of the cup 4 during a part of the reciprocation of the rod 11, and the upper end of the slot has a laterally offset portion 8^b which is adapted to accommodate the pin 10, while the cup 4 is swinging into its open or its closed position, this taking place during the remainder of the stroke of the rod 11. The cam 9 fixed to the shaft 7 of the lower cup 5 has a cam slot 9^a therein with an offset 9^b, the cam 9 and its slot being similar to the cam 8 and its slot, except that these cams are fixed in relatively reverse positions on the shafts of the respective cups. A pin or projection 12 on the lower end of a rod 13 operates in the cam slot 9^a, the rod 12 being mounted to reciprocate through a relatively fixed guide or sleeve 14, and the upper end of the rod 13 is connected by a pivot 15 to a link or pitman 16, the upper end of the latter pivotally engaging the pin 10. The rod 11 may be guided by a bracket 17 which may be fixed to a wall or other suitable support, and the upper end of this rod is pivotally or otherwise operatively connected to an arm 18 of a dumping lever 19, the latter being pivotally mounted at 20 on a wall or other suitable support. Means is also preferably provided for limiting the range of movement of the lever 19, a bracket 21 being provided for this purpose in the present instance which has limit stops 22 and 23 which are adapted to limit the range of swinging movement of the arm 18 of the dumping lever. Suitable means is provided for normally holding the lever 19 in the position shown in Figure 1, a tension spring 24 being provided for this purpose in the present instance, one end of which is attached to a bolt 25 or other suitable point of attachment on the outside of the discharge pipe 3, and the upper end of which is hooked on the lower end 12 of the rod 13, this spring acting in a direction to draw the rod 13, the link or pitman 16, the rod 11, and the parts associated with these elements downwardly.

The mode of operation of the device is as follows: Normally, the lever 19, the upper and lower cups, and the operating mechanism occupy the position shown in Figure 1, the upper cup 4 being then closed and the lower cup 5 open. When the handle of the lever 19 is depressed into dumping position, the rod 11 is pulled upwardly, the first part of the upward movement of the rod 11 causes the pin 10 attached thereto to move 70 idly upwardly in the cam slot 8^a for the upper cup 4, so that this upper cup remains in closed position, but during this initial part of the upward movement of the rod 11, the pin 12 on the rod 13 which also moves 75 upwardly with the rod 11 acts on the cam 9 of the lower cup 5 to swing the lower cup into closed position, so that when the lever 19 reaches about the middle of its swing, both upper and lower cups will be in closed 80 position, the parts being shown in this position in Figure 4. As the dumping movement of the lever continues, the pin 12 of the rod 13 will travel in the portion 9^a of the cam slot which is then aligned with the direction of movement of the rod 13, so that the lower cup 5 is held in its closed position, while at the same time the pin 10 on the lower end of the rod 11, which has then 85 reached the upper end of its cam slot 8^a, will begin to swing the upper cup 4 into open position, and the opening movement of the upper cup continues until the lever 19 has reached the limit of its stroke, at which time the upper cup will be open and the lower cup closed, the parts being shown in this position in Figure 5. Release of the lever 19 enables the spring 24 to restore the cup operating mechanism to its initial or normal position, the first part of the restoring motion of the mechanism causing the upper cup 4 to close, while the lower cup 5 remains closed and the continued restoring movement of the operating mechanism causing the lower cup 5 to open while the upper 95 cup 4 remains closed, the cups being normally held in this position by the spring 24.

By operating the cups in the manner described, it will be understood that no passageway is left at any time for a draft of air upwardly through the toilet pipe, and hence bacteria or odors dangerous to the health can not be blown into the toilet compartment or any other part of the car or vehicle. Thus, when the upper cup or valve 115 is opened to dump the excreta, the lower cup or valve is fully closed, and when the lower cup or valve is opened to discharge the excreta, the upper cup or valve is fully closed, neither cup or valve commencing its opening movement until the other cup or valve has assumed its fully closed position.

I claim as my invention:—

1. In a toilet having a pair of pivoted cups controlling the outlet thereof, means for operating said cups whereby one cup is closed after which the other cup is opened, comprising cams connected to the respective cups, and a pivotally jointed rod, means for individually guiding the sections to recipro- 120

cate longitudinally, said rod sections being provided with projections which cooperate individually with the respective cams.

2. In a toilet having a pair of pivoted cups controlling the outlet thereof, means for operating said cups whereby one cup is closed, after which the other cup is opened, comprising cams connected to the respective cups, a rod embodying pivotally connected sections, means for individually guiding

said sections to reciprocate longitudinally, said sections carrying projections which cooperate with the respective cams, and a link pivotally connecting the sections of the rod and permitting angular movement of one of the sections of the rod relatively to the adjacent section thereof. 15

In testimony whereof I have hereunto set my hand.

JAMES H. McCALL.
